CONTAINER

Rex P. Mulligan, Washington, D. C., assignor to
Sylvania Industrial Corporation, Fredericksburg, Va., a corporation of Virginia

Application March 17, 1932, Serial No. 599,414

6 Claims. (Cl. 206—41)

This invention relates to containers for articles and more particularly to containers adapted for the packaging of tobacco and like substances.

It has been the usual practice to sell loose tobacco and like substances, for use in pipes or hand-making of cigarettes, in tin boxes or like packages which prove very inconvenient in the filling of pipes, cigarettes, etc. Pouches and like receptacles have been provided of different materials such as animal skins, silk and oilskin. Such pouches either have permitted the passage of moisture to such an extent as to materially affect the moisture content of the tobacco as in the case of skin and silk pouches, or they have become stiff and unwieldy in cold weather and crack when folded, as is the case with pouches formed from oilskins. It is an object of the invention to provide a container in which such disadvantageous characteristics are in a large measure absent.

Another object of this invention is to provide a package in which substances, such as tobacco and the like, may be packaged and sold, the package also serving after the sale as a convenient container of pocket size from which smoking devices, such as pipes and the like, may be filled.

It is a further object of this invention to provide a package for loose tobacco and like substances in which the tobacco may be sold and which may afterwards be employed as a container, preferably of pocket size, to maintain the tobacco substantially at its original moisture content.

Other objects of the invention will in part be obvious and will in part appear hereinafter.

The invention accordingly comprises an article of manufacture possessing the features, properties, and the relation of elements which will be exemplified in the article hereinafter described and the scope of the invention will be indicated in the claims.

The pouch or container of the present invention overcomes the above-mentioned difficulties; since it eliminates the necessity of a tin box or like package for tobacco by providing a package in which tobacco may be sold and which may also be employed as a pocket pouch for conveniently handling the tobacco and maintaining it fresh for substantial periods of time. This is accomplished by forming a pouch or container having a pocket and a closing flap, preferably from a flexible transparent material such as a sheet of cellulosic material, e. g., regenerated cellulose or a cellulose derivative, as for instance, ethyl cel-

lulose, methyl cellulose, nitrocellulose, cellulose acetate, or poly-vinyl compounds, which may be combined with moistureproofing compositions. The pouches are formed, preferably with a flap of like material extending from the open end of the pocket of the pouch.

In practice, the pouch with its contents may be rolled or folded and sealed by a suitable adhesive, or preferably heat-sealed along a line adjacent the mouth of the pocket, the flap being wrapped around the pouch to further protect the contents. The flap may then be fastened by a suitable means, such as a seal or sticker. Identification marks or printing may be applied to the outside of the package.

For a fuller understanding of the nature and objects of the invention, reference should be had to the following detailed description taken in connection with the accompanying drawings, in which:

Fig. 1 illustrates a manner of cutting the blanks of Fig. 2 from a sheet of material without substantial waste;

Fig. 2 is a view of the blank from which the pouch of Fig. 3 is formed;

Fig. 3 is a perspective of one modification of the container of the present invention when empty and unrolled;

Fig. 4 is a front view of the same container;

Fig. 5 is a rear view showing the overlaps by which the pocket of the pouch is formed;

Fig. 6 is a perspective of the container when filled and sealed but not rolled;

Fig. 7 is a perspective of the container of this invention when filled, sealed and rolled;

Fig. 8 is a perspective of the container of Fig. 7 when placed within an outer dispensing container, preferably formed of pasteboard, paper, or other material; and

Fig. 9 is a perspective of an outer container, such as a humidor or a metal receptacle in which a plurality of the containers described herein may be placed.

With particular attention to the construction of the pouch shown in Fig. 3, reference is made to Figs. 1 and 2 wherein a method of cutting the pouch blanks from a sheet of material and a blank so cut are shown. Reference number 1 indicates a sheet of material of flexible nature from which the pouch blanks A, B, C, etc. are cut by any suitable apparatus, such as a series of cutting knives mounted on a roller. This method of cutting involves substantially no waste of material. The individual blanks thus formed have a main body portion 2 and projecting por-

tions 3 and 4 (see Fig. 2). The projections 3 and 4 are folded along the lines 5-5, 6-6, and 7-7, the lines 6-6 forming the inner line of a bellows fold which permits the expansibility of the pocket fold as shown in Fig. 3. The blank is then folded along the line 8 to make the bellows fold. The portions of the projecting portions 3 and 4 lying outside the line 7-7 furnish overlaps which are secured to the rear face of the blank by a suitable adhesive so as to form the pocket proper 12 as shown in Fig. 3. Since the lower edge of the blank falls on the line 9 when folded, there is formed a flap portion 11, the purpose of which will be herein-after described.

15 The flap may be provided with smooth, un-cut edges by binding with a suitable tape or hem to prevent the material from tearing. In Fig. 4 a tape 14 of the same or different material and/or color from that used in the pouch is folded about 20 and attached to the edges of the flap, preferably by use of a suitable adhesive. If desired, the pouch blank may be cut as shown in Fig. 2 to provide an edge flap 15 which may be folded along the lines 16 and 17 to provide a binding 25 hem 18 as shown in Figs. 3 and 5.

In employing the package above described, it is first filled with the tobacco or other substance to be sold. Then the pocket is sealed along the line 9 adjacent the mouth thereof, the 30 pocket rolled or folded and the flap 11 wrapped or folded around it. A tape or string 13 may be provided to facilitate the breaking of the seal along the line 9. The flap 11 may be secured by heat-sealing, or an adhesive or a sticker may be used. Suitable printing matter or designs may be applied to the exterior of the package. The package as formed (Fig. 7) may be thus sold, or it may be sold singly or in groups with other like packages in a box or other container as 35 shown in Figs. 8 and 9. The outer container, such as the box of Fig. 8 on the humidor of Fig. 40 9, may be sealed.

Obviously, the container of the present invention is possessed of many advantages. It may 45 be used directly as the sales container and, after the sale, it serves as a convenient pouch for both using the tobacco and maintaining it at the proper moisture content, being of a size sufficiently small to be carried in the pocket. With 50 respect to its use as a sales container, the pouch is particularly attractive by reason of the transparent and clear character of the material employed, thus enabling the contents to be inspected without damage or harm. Furthermore, when 55 material of the nature described, i. e., such as regenerated cellulose or other cellulose derivatives are employed, attractive and pleasing designs in addition to any desired lettering may be printed thereon. If desired, portions or all of the container may be rendered opaque and of different 60 colors to render the appearance of the package more colorful and attractive.

In addition to its utility as above pointed out, the material employed is of a nature that is not 65 responsive to temperature changes, and the material remains flexible without cracking at substantially all temperatures experienced under normal weather conditions.

While the present invention has been described 70 with some degree of exactness and detail, it is to be understood that the invention is not limited to such detail, but inasmuch as certain changes may be made in the above article and different embodiments of the invention could be made

without departing from the scope thereof, it is intended that all matter contained in the above description or shown in the accompanying drawings shall be interpreted as illustrative and not in a limiting sense.

5

I claim:

1. A merchandise container for tobacco or other substances comprising a sheet of transparent, moistureproofed, flexible material formed into a pouch having a pocket adapted to receive the substance to be merchandised and a closing flap extending beyond the mouth of said pocket, said pocket being initially sealed along a line adjacent the mouth thereof to preserve the substance contained therein and, after the seal has been broken, being closed by folding.

2. A merchandise container for tobacco or other substances comprising a sheet of transparent, flexible material combined with a moistureproofing composition, formed into a pouch having a pocket adapted to receive the substance to be merchandised and an elongated closing flap extending beyond the mouth of said pocket, said pocket being initially sealed by heat-sealing the sheet material along a line adjacent the mouth thereof to preserve the substance contained therein and being closed after the seal has been broken by having the flap wrapped around the same.

3. A merchandise container for tobacco or other substances comprising a sheet of transparent, moistureproofed, flexible material formed into a pouch having an expandable pocket adapted to receive the substance to be merchandised and an elongated closing flap extending beyond the mouth of said pocket, said pocket being initially sealed along a line adjacent the mouth thereof to preserve the substance contained therein and being closed after the seal has been broken by having the flap wrapped around the same.

4. A merchandise container for tobacco or other substances comprising a sheet of transparent, moistureproofed, flexible regenerated cellulose formed into a pouch having an expandable pocket adapted to receive the substance to be merchandised and an elongated closing flap extending beyond the mouth of said pocket, said pocket being initially sealed along a line adjacent the mouth thereof to preserve the substance contained therein and being provided with means for breaking the seal, said pocket being closed after the seal has been broken by having the flap wrapped around the same, the flap and the edge of the pocket mouth being provided with a hem.

5. A tobacco package comprising a sheet of transparent, moistureproofed, flexible material formed into a pouch having a pocket containing tobacco, and a closing flap extending beyond the mouth of said pocket, said pocket being initially sealed along a line adjacent the mouth thereof to preserve the tobacco contained therein and, after the seal has been broken, being closed by folding.

6. A tobacco package comprising a sheet of transparent, moistureproofed, flexible material formed into a pouch having an expandable pocket containing tobacco and an elongated closing flap extending beyond the mouth of the pocket, said pocket being initially sealed along a line adjacent the mouth thereof to preserve the tobacco contained therein and being closed after the seal has been broken by having the flap wrapped around the same.

REX P. MULLIGAN.
